CLAIM

The ornamental design for a file sorter, as shown and described.

DESCRIPTION

FIG. 1 is a perspective view of file sorter of the first embodiment showing my design;

FIG. 2 is a front view thereof;

FIG. 3 is a bottom view thereof;

FIG. 4 is a top view thereof;

FIG. 5 is a rear side view thereof;

FIG. 6 is a left side view thereof;

FIG. 7 is a right side view thereof;

FIG. 8 is a perspective view of file sorter of the second embodiment;

FIG. 9 is a front view thereof;

FIG. 10 is a bottom view thereof;

FIG. 11 is a top view thereof;

FIG. 12 is a rear side view thereof;

FIG. 13 is a left side view thereof;

FIG. 14 is a right side view thereof;

FIG. 15 is a perspective view of file sorter of the third embodiment;

FIG. 16 is a front view thereof;

FIG. 17 is a bottom view thereof;

FIG. 18 is a top view thereof;

FIG. 19 is a rear side view thereof;

FIG. 20 is a left side view thereof; and,

FIG. 21 is a right side view thereof.
